HIGH-SPEED RAILWAY CAR TRUCK

Cyrus J. Holland and Knute Edahl, Chicago, Ill.,
assignors, by direct and mesne assignments, to
Holland Company, a corporation of Illinois

Application July 3, 1942, Serial No. 449,558

10 Claims. (CL. 105—185)

This invention relates to railway equipment, and more particularly to truck construction for railway cars.

One of the objects of the invention is the provision of a new and improved truck having novel means for mounting the bolster so that shocks due to the swaying of the load, or sudden lateral movements of the axles in rounding curves, will be cushioned, with the result that the wear on the axle collars and journal bearings will be reduced to a minimum.

Another object of the invention is the provision of a new and improved truck having novel means for shifting the supporting fulcrum for the load while rounding curves.

Another object of the invention is the provision of new and improved means for banking the truck frame while the car is traveling around curves at high speeds.

A still further object of the invention is the provision, in a spring plankless type of truck, of new and improved means for supporting the side frames from the journal boxes of railway axles so that the frames are movable laterally relative to the journal boxes, or are slightly canted and the outer one being elevated on rounding curves, thereby cushioning the shocks incident to such constructions on entering curves at high speeds.

A further object of the invention is the provision of a new and improved truck having swing hangers for supporting the side frames directly from the journal boxes instead of thus supporting the bolster from the truck frame.

Another object of the invention is the provision of a new and improved truck that is inexpensive to manufacture, easily assembled, and so constructed that the load is resiliently supported and cushioned against shocks due to sudden or violent lateral movement of the axles incident to the truck entering curves at high speeds.

Other and further objects and advantages of the invention will appear from the following description, taken in connection with the accompanying drawings in which

Fig. 1 is a side elevation of a railway truck disclosing the invention;

Fig. 2 is a plan view with parts in section, on the line 2—2 of Fig. 1, and parts broken away;

Fig. 3 is an end elevation of the truck looking in the direction of the arrows 3—3 of Fig. 1, and with parts in section and parts broken away;

Fig. 4 is a vertical section of one of the journal boxes, showing the side frame in normal position;

Fig. 5 is a similar view, but showing the side frame in the position it assumes when the truck is rounding curves at high speed;

Fig. 6 is a view similar to Fig. 4, but showing a modified form of construction;

Fig. 7 is a view similar to Fig. 6, but showing another modified form of construction;

Fig. 8 is a view similar to Fig. 4, but showing a still further modified form of construction;

Fig. 9 is a section on the line 9—9 of Fig. 8;

Fig. 10 is a view similar to Fig. 8, but showing a further modified form of construction;

Fig. 11 is a section on the line 11—11 of Fig. 10.

The A. A. R. conventional truck is designed to have its side frames remain in vertical position under any and all conditions, and in the so-called "spring plankless" type of truck the lateral movement of the bolster is in consequence very limited, which results in rapid wear on axle

collars and journal bearings, thereby increasing the length of movement of the side frames so that lateral thrusts become shocks against the collars and bearings. Such wear permits the application of the load to shift outwardly on the

ends of the axle on curves, thus increasing the bending moment on the axle and thereby causing a more rapid increase in fatigue and crystallization of the journal while in use. The safety and life of the axle is thereby decreased, resulting in damage to the car body and impairing the safety of the axle, not to mention the evil effects of the violent shocks to the lading and track.

The present invention seeks to remedy these difficulties by the provision of novel means which permits a limited rocking or yielding of the side frames, slight banking of the bolster, and shifting of the point of application of the load on the journals on rounding curves at high speed.

Referring now to the drawings, the reference character 3 designates a railway car comprising a truck 10 having a pair of side frames 11, one at each side of the truck, and the axles 13, 14, having the journal boxes 15, 16, on the ends thereof. Each journal box contains the conventional brass member or bearing 5 and a wedge 6 (Figs. 4 and 5). The bearings 5 engage the journals 7 of the axles 13, 14. Collars 8 and shoulders 9 on the axle journals 7 limit the relative lateral movement of the bearings and journals.

The conventional journal bearings or brass members and associated wedges are omitted from certain figures of the drawings for the sake of clearness. The side frames are each provided with downwardly extending pedestals 17, 18, at

each end thereof, as is usual in such constructions. These pedestals slidably engage at opposite sides of the corresponding journal boxes, and each journal box is provided with outer and inner shoulders 19, 21, respectively, Fig. 2, which limit the lateral movement of the side frames, respectively. Each set of pedestals is connected by a tie member 22 at its lower end.

Each side frame has a compression member 23 at its upper portion, and a tension member 24 at its lower portion, which cooperate with vertical columns 25, 26, Fig. 1, to form a bolster opening 27 through which one end of the bolster 28 extends. The bolster is provided with shoulders 29, 31, at its sides at each end thereof, Fig. 2, which slidably engage the corresponding columns 25, 26. The lower part of each opening 27 is enlarged, as at 32, to permit insertion and removal of the bolster 28 from the frame.

The tension member 24 is hollow or channel shape, and is provided with pockets or openings 40 into which suitable springs 33, of a spring assembly 34, extend and are seated on the lower wall 35 of the tension member, as more clearly shown in Fig. 3 of the drawings. The springs 33 of the spring assembly 34 engage beneath the bolster 28 for resiliently supporting the same on the truck. In the conventional railway truck the spring assembly is supported on the upper wall of the tension member, and consequently the springs are much shorter than the springs 33 of the present construction. By extending the length of the springs a much softer riding truck is provided. In order to strengthen the tension member and to form pockets for positioning the lower ends of the springs, suitable upstanding webs 36, 37, extending longitudinally and transversely, are provided, as shown in Figs. 1 and 3 of the drawings.

In rounding curves at high speeds, with trucks having side frames held rigidly in vertical planes, as where they are integral with the journal boxes, the centrifugal force of the car body and the lading tend to move the supporting bolster outwardly relative to the curve, and this movement carries with it the side frames and journal boxes and brings the bearings 5 into contact with the collars 8 and shoulders 9 of the journal boxes. When the flanges of the wheels first engage the rails on the curve the car body, by centrifugal action, causes the bearings 5 on the outer side of the curve to come abruptly into contact with the collar 8 of the outer journal, and the bearing 5 on the inner side of the curve to abruptly engage the shoulder 9 on the inner side of the curve, thus producing a shock to the car body and to the lading. As a result of these shocks and the radial outward movement of the side frames, the collars 8 on the outer ends of the outer journals, and the shoulders 9 on the inner journals, together with the bearings 5, will become worn, and as they are worn the shocks become greater.

Suitable means are provided in the present invention for minimizing the wear on these collars, shoulders and bearings for reducing the shocks incident to the truck entering curves during the normal running operation of the car. Suitable means are provided for permitting a rocking movement of the side frames relative to the bolster for yieldingly resisting the outward movement of the body on rounding curves, and as a consequence of this arrangement the shocks are greatly lessened, and the wear on the bearings 5, collars and shoulders 8 and 9 of the journals,

is reduced to a minimum. The form of construction of the truck for accomplishing this function will now be described.

In the form of the device shown in Figs. 1 to 5 inclusive, the journal boxes 16 are each provided with an upwardly extending load supporting arm 38. These supporting arms may be, and preferably are, integral with the journal boxes, and have provided on their upper ends a plurality of cam teeth or projections 39, 41, which are rounded at their ends, as shown more clearly in Figs. 4 and 5 of the drawings. Since these arms are all alike only one need be described. A curved recess 42 is provided between the projections 39, 41, which is adapted to be engaged by a downwardly extending projection 43 on the side frames at the corresponding end thereof. This projection is curved at its lower end, but on a shorter radius than the recess 42, so that the projection 43 may rock within the recess 42 a limited amount without contacting the side walls of the recess. The projection or tooth 41 extends upwardly beyond the plane of the tooth 39, and is adapted to engage within a curved recess 44 when the lower portions of the side frames are moved outwardly. In the normal position of the side frames they are in vertical planes, and the curved lower end of the tooth 43 engages the bottom of the recess 42, as shown in Fig. 4. In this position the upper curved end of the tooth 41 is spaced from the recess 44, as shown in said figure.

By means of this arrangement a slight rocking movement of the side frames may be had without the tooth 41 coming in contact with the bottom of the recess 44. After the initial lateral movement of the frame the tooth 41 will engage the bottom of the recess 44, and any further outward movement of the frame will cause the same, together with the car and lading, to be elevated 40 on that side, thereby yieldingly resisting any further outward movement of the frame. In other words, the parts are so constructed and arranged that in normal operation on straight away track the side frame pivots at 42, 43, and is shifted to 45 41, 44, on the outer journal boxes on curves at high speed. The projection 39 is normally spaced a greater distance from the under surface 45 of the side frame than the distance between the tooth 41 and the recess 44, so that the projection 39 does not at any time engage the recess 44.

It will be noted that when the bolster on which the body is mounted moves laterally outwardly, due to centrifugal force of the weight of the car and lading, the shoulders 29 and 31 thereon will force the side frames radially outwardly in the same direction, thus tilting the side frames; and after the initial outward movement of the bolster the weight of the body and lading will be supported by the projections 41 of the side frames that are on the outer side of the curve, and the parts 43 and 42 will be spaced apart, thus shifting the supporting fulcrum inwardly on the journal boxes, so that even if the collars 8, shoulders 9 and bearings 5 be worn the application of the weight of the lading, due to the centrifugal action in rounding a curve, will not be shifted outwardly on the journal box beyond the normal position. The bearings on the inner side of the curve will, of course, be shifted toward the axis, and thus the point of support from the inner journal is likewise shifted inwardly along the axle.

This is considered an important feature of the invention, because where the load is shifted outwardly on the journal box it will result in greater

stresses on the axle, thus tending to cause earlier crystallization of the metal. Furthermore, the shifting inwardly of the supporting fulcrum causes a banking of the car, which produces an effect similar to increasing the elevation of the outer rail, thereby partially overcoming the evil effects of this centrifugal action.

It will also be noted that on entering curves at high speeds this swinging movement of the side frames, together with the slight elevation of the same on the outer side of the curve, will constitute a cushioning arrangement for preventing shocks to the car and to the lading. Furthermore, this shifting of the load supporting fulcrum on the journal box and the banking of frames will greatly reduce the wear on the collars 8 and shoulders 9 of the journals.

In order to provide clearance for the rocking movement of the side frames on curves the shoulders 29 and 31 at each end of the bolster may be sloped or rounded off at their upper and lower portions for accommodating this movement, as indicated at 46, 47, of the drawings (Fig. 3). Likewise, the shoulders 19, 21, on the journal boxes may have their upper and lower portions inclined or curved, as shown at 49 and 50 in Figs. 4 and 5, for providing clearance for the swinging movement of the bolster. This swinging movement is not very great, but is sufficient to soften the shocks incident to the contacting of the bearings with the shoulders on the axle journals. This clearance is shown more or less exaggerated for the sake of clearness.

The form of construction shown in Fig. 6 differs from that just described in that a rocker member 48 is employed instead of the rigid member 38 previously described. In this form of construction the journal box 18^a is provided with a short upwardly extending projection 38^a, which is provided with a curved recess 51 adapted to receive the lower curved end 52 of the rocker member 48. This member has upwardly extending teeth or projections 39^a, 41^a, corresponding to the projections 39, 41, of the construction shown in Fig. 4. The side frame 11^a is provided with a downwardly extending projection 42^a, which engages in a recess 42^a for supporting the side frame in normal position. The projection 41^a is adapted to engage in a recess 44^a when the lower portion of the side frame is rocked outwardly by the centrifugal action of the car and lading through the operation of the bolster, as in the previous construction.

This construction, as in that shown in Fig. 4, is adapted to shift the supporting fulcrum from the projection 42^a and recessed surface 42^a to the projection 41^a and recess 44^a on rounding curves to the right at high speeds, as in the previous construction. In this form, since the rocker member 48 is free to rotate the banking of the bolster may be more pronounced than in the previous construction. In both forms the initial movement due to centrifugal action will not change the point of application of the load. The arrangement of the rocker members on the journal boxes on the opposite side of the truck is reversed from that shown, so that on left turns the right side of the truck and car are elevated or banked.

The form of construction shown in Fig. 7 differs from those already described in that there is very little banking of the bolster and truck frame on rounding curves. The side frames, however, are so constructed that they may rock, as in the previous constructions. In this form

the journal box 18^b is provided with an upstanding projection 38^b, terminating in a spherical bearing member 53 that engages a recess 54 in the side frame 11^b. It will be noted that in rounding curves the side frame 11^b may rock from the vertical, thus tending to elevate the center of gravity of the load, thereby providing a yielding resistance for reducing shocks due to contact of the flanges of the wheels with the track on entering curves.

In Figs. 8 and 9 is shown a further modified form of construction, and in this form link mechanism is provided for banking the truck frame and for providing a yielding action for reducing shocks and wear on the collars or shoulders of the axle journals. As shown, the journal boxes 18^c are provided with upstanding projections 38^c, each of which has a curved recess 55 forming a bearing in which is pivoted a journal 56 of an inverted U-shaped link member 57.

The side frames are hollow, as in the previous constructions, and are provided with webs 58, 59, at opposite sides of the upwardly extending projection 38^c, as shown more clearly in Fig. 9 of the drawings. The downwardly extending arms 61, 62, of the inverted U-shaped member 57 have at their lower extremities projections 63, 64, extending laterally in opposite directions, and each is provided on its upper surface with upwardly extending tooth members 65, 66, having a recess 67 between them, as clearly shown in Fig. 8. The webs 58, 59, are provided with a downwardly extending tooth or projection 68, which is adapted to seat in the recess 67 for supporting the side frame in its normal vertical position. There is a recess in each of the webs 58, 59, at opposite sides of the projection 68, as shown at 69 and 71. The projections 68, 65 and 66, and the corresponding recesses, are so constructed and arranged that the frame 11^c may have a limited lateral movement in both directions without the projections 65, 66, engaging in the corresponding recesses. This will compensate for the usual lateral movement or nosing of the truck during travel on straight tracks. Any further outward movement of the frame or inward movement of the axle will cause the projection 68 engaging the recess 69 to abruptly elevate the side frame, thereby banking the truck.

It will be seen that in the initial relative lateral movement of the side frames and axles the frames swing about a predetermined radius, and in the final pivotal movement they swing about materially shortened radii on the outer side, so that the frames are banked on curves.

Due to the swinging support for the load the shocks incident to the coming in contact of the journal box bearing with the collars or shoulders of the journals or axles will be greatly reduced, as in the previously described constructions.

The form of construction shown in Fig. 10 differs from that shown in Figs. 8 and 9 in that the construction is such that the U-shaped swinging member is inverted from the position shown in those figures. In this form the journal 56^a of the U-shaped member 38^a engages a recess or bearing 72 on the lower end of a web 73 integral with the side frame 11^a. The ends 74 of the U-shaped member 38^a are turned outwardly, as in the previous construction, but are above the journal 56^a and are turned outwardly in opposite directions. Each of these extensions 74 is provided with a downwardly extending projection or tooth 75 and a downwardly extending tooth 76 having a curved recess 77 between the two

which forms a bearing for a projection or tooth 78 on an upwardly extending projection 79 at each side of the swing hanger or U-shaped member 38. The projection 78 is provided with a recess 81, which is adapted to be engaged by the projection 76 when the side frame is moved outwardly or the axle is moved inwardly or to the right, as shown in Fig. 10, thus banking the truck frame on turning to the right at high speed. The arrangement is reversed at the opposite end of the axle, so that left turns will bank the truck on that side, thus cushioning the shocks in the same manner as described above. 10

We claim as our invention:

1. In a railway truck, a plurality of axles, journal boxes on the end portions of said axles, a truck frame comprising a pair of side frames, arms extending upwardly from said journal boxes, each arm having upwardly extending teeth or projections rounded at their upper portions and separated by rounded bearing recesses, said frames being provided with recesses into which said arms extend and having above each arm a downwardly extending rounded tooth or projection engaging in the corresponding bearing recess, said side frame having rounded recesses at opposite sides of the rounded tooth, said teeth and engaging recesses being so constructed and arranged that when said axle is caused to move inwardly on curves the truck frame will be banked and the point of application of the load will be shifted inwardly on the outer side of the truck frame. 20

2. In a railway truck, a plurality of wheeled axles, journal boxes for said axles, a side frame at each side of the truck, a bolster between said side frames, arms projecting upwardly from said journal boxes, swing hangers journaled on said arms, and tooth cam engaging members between said swing hangers and said frame members so constructed and arranged as to bank said bolster and frames when said truck travels around curves at high speeds. 30

3. In a railway truck, a plurality of wheeled axles, journal boxes for said axles, a side frame at each side of the truck, a bolster between said side frames, arms projecting downwardly from said side frames and each provided with a bearing at its lower end, swing hangers journaled in said bearings, supports rigidly connected to said journal boxes and extending upwardly therefrom and provided with cam teeth, and cam teeth members on said swing hangers engaging between the cam teeth on said supports, said teeth being so constructed as to bank said side frames on rounding curves at high speed. 45

4. In a railway truck, a plurality of wheeled axles, journal boxes on said axles, projections extending upwardly from said journal boxes, side frames free for lateral swinging motion in response to centrifugal force on track curves, and cooperating means on said side frames and journal boxes including said projections for elevating and shifting inwardly the points of support of the outer side frame in response to centrifugal swinging of the side frames in rounding curves at high speed. 50

5. In a railway truck, a pair of wheeled axles, journal boxes for said axles, and side frames on opposite sides of the truck, each of said side 70

frames being mounted on the corresponding journal boxes for inward rocking movement through a range of levels in response to inward centrifugal force and outward rocking movement with sufficient inward shifting of the point of support to result in a higher range of levels in response to outward centrifugal force whereby each of the side frames will have a banking effect when traveling around a curve on the outer side of the curve. 10

6. In a railway truck, a pair of wheeled axles, journal boxes for said axles, side frames on opposite sides of the truck, and means effective between said side frames and the corresponding journal boxes to support the side frames, to permit the side frames to rock laterally in response to centrifugal force and also in response to centrifugal force to cause the side frame on the outside of a curve to shift its fulcrum of support inward and take a position of greater elevation than the side frame on the inside of the curve thereby to provide a banking action. 15

7. In a railway car, a car body, a truck for supporting said body, a pair of wheeled axles for said truck, a journal box on each end of said axles, a side frame at each side of said truck, a bolster loosely mounted on said side frames, and means for supporting each of said side frames from said journal boxes for rocking movement with shift in the fulcrum of support of the side frame opposite to the direction of rocking movement, said fulcrums shifting inwardly by relatively great amounts in response to outward rocking movement thereby causing banking of said bolster on curves. 25

8. In a railway truck, a pair of wheeled axles, journal boxes on the ends of said axles, side frames at the sides of said truck, arm members extending upwardly from said journal boxes, and rocking cam means between the upper portion of each of said side frames and the corresponding arm supporting the side frame for rocking movement with shift in the point of support in opposite direction to the rocking movement, the inward shift being of large relative magnitude with consequent relative elevation of the outwardly rocked side frame for banking action on a curve. 35

9. In a railway truck, a pair of wheeled axles, journal boxes on the ends of said axles, a side frame at each side of the truck, a bolster carried by said frames, and rocking members interposed between said frames and the corresponding journal boxes for movably supporting the frames with differential shifting of support points with respect to outward and inward frame movements thereby to vary the relative elevations of the side frames for banking said bolster on curves. 45

10. In a railway truck, a pair of wheeled axles, journal boxes on the ends of said axles, a side frame at each side of the truck, a bolster carried by said frames, and swingable hangers for movably supporting said side frames from the corresponding journal boxes, said swinging hangers being shaped to provide differentially shifting support points with respect to inward and outward frame movements thereby to bank said bolster in response to centrifugal force on curves. 50
